(57) **CLAIM**

The ornamental design for a shoe sole, as shown and described.

DESCRIPTION

FIG. 1 is a bottom plan view of a shoe sole showing our new design;

FIG. 2 is a side view thereof;

FIG. 3 is another side view thereof;

FIG. 4 is a front view thereof, and,

FIG. 5 is a rear view thereof.

The broken lines in the Figures show environment for illustrative purposes only and form no part of the claimed design. The broken lines surrounded by claimed surfaces depict portions of the shoe sole that form no part of the claimed design. The dot-dashed lines in the Figures show the border around portions of the subject matter being claimed.
